Attorney

UNITED STATES PATENT OFFICE.

CLARA M. JAQUITH, OF DENVER, COLORADO.

DUST BAG FOR VACUUM CLEANERS.

Application filed May 28, 1924. Serial No. 716,291.

To all whom it may concern:

Be it known that I, CLARA M. JAQUITH, a citizen of the United States, residing at Denver, the city and county of Denver and 5 State of Colorado, have invented certain new and useful Improvements in Dust Bags for Vacuum Cleaners; and I do declare the following to be a full, clear, and exact description of the invention, such as will enable others skilled in the art to which it 10 pertains to make and use the same, reference being had to the accompanying drawings, and to the characters of reference marked thereon, which form a part of this 15 specification.

This invention relates to improvements in dust bags for vacuum cleaners.

It is well known to all who employ ordinary vacuum cleaners that these are far from 20 being as cleanly and as sanitary as they should be. The main reason for this is that the dust is discharged from the blower into a bag, the walls of which must be sufficiently porous to permit the air to escape. 25 The walls of the dust bag act as a strainer whose function it is to retain the dust while the air escapes through the walls and into the room. It is, of course, impossible, with the ordinary cloth bag, to remove all of 30 the dust from the air, as much of the dust and dirt is in the form of an impalpable powder so fine that it passes freely through the meshes between the threads. This fine dust often carries the disease germs which 35 by this means become widely scattered. The proof that dust passes through the walls of the bag can readily be produced, as it is only necessary to carefully dust articles of furniture before the cleaner is used and then 40 to note how much dust settles upon this furniture after the cleaning is over.

It is evident that the ideal bag would be one that would remove all of the dust from the air so that the latter, as it reentered 45 the room, would be entirely clean. It has, however, been impossible to produce material that will screen the dust out of the air completely.

It is the object of this invention to produce a dust bag that shall be so constructed 50 that the air which leaves the same shall be filtered to such an extent that it is for all practical considerations, clean.

My invention, briefly described, consists 55 in making the bag of very closely woven fabric which is practically air-tight or the

fabric may be rubberized or filled with some material that renders it air-tight. For the purpose of permitting the air to leave the bag as fast as it enters, I provide a vent 60 which is provided with an air filtering means. This vent is preferably formed in the manner which will be hereinafter more fully described and comprises a box which is adapted to contain filtering material, such as a wet sponge, wet felt or cotton waste or any other suitable filtering material. The box is provided with means which will cause 65 the air to travel through the filtering material. 70

In order more clearly to describe my invention, I shall have reference to the accompanying drawing in which one embodiment thereof is shown, and in which:

Fig. 1 is a side elevation of a vacuum 75 cleaner showing the bag constructed in accordance with my invention;

Fig. 2 is a section of the air filtering device; and

Fig. 3 is a view similar to that of Fig. 2, 80 but showing the filtering material in place.

Numeral 1 represents a dust bag which may be similar in shape and size to those now in common use. This bag differs from those ordinarily employed in this, that it 85 is air-tight or substantially so. The vent 2, through which the air leaves the bag, comprises a metal box having a wall 3 provided with outwardly extending annular flanges 4 and 5 between which the material 90 6 of the bag is clamped as by means of rivets 7. The bottom 8 of the box is bent inwardly and has a central opening 9 which is closed by a woven wire screen 10 or which may be 95 closed by any other suitable foraminated material.

A cover comprising a ring 11, to which is secured a woven wire top 12, serves to close the box. The box just described is designed 100 to contain the filtering material 13 which may be a wet sponge, wet felt or wet cotton waste. In fact, the filtering material may be any suitable material that will permit the air to pass through it. Since the bottom 105 of the box is curved upwardly towards the cover, the air will enter the filtering material close to the center of the same and will be obliged to pass through it instead of around it. As the filtering material is wet, the dust in the air will adhere to the moist 110 filtering material and the air, as it enters the room, will be clean.

It is evident that many specifically different designs or filters may be invented, any one of which will serve the same purpose as the one described, and I wish it to be understood that the one described above is illustrative merely and is to be regarded as an element of the combination.

From the above, it is apparent that I have produced an improved dust bag for vacuum cleaners that will filter the air as it leaves the bag so as to remove from it all dust and dirt, thereby converting the vacuum cleaner into really cleanly and sanitary devices.

Having now described my invention, what I claim as new is:

1. A dust bag for vacuum cleaners comprising, in combination, a flexible, substantially air tight fabric bag adapted to be secured to the exhaust opening of a vacuum cleaner and to receive the dust and dirt from the latter, said bag having an opening, a metal container projecting from opposite sides of the wall of said fabric bag and located within the opening and secured to the edges thereof by means forming an air tight seal, said container being adapted to receive a filter medium, the top and bottom of said container being foraminated whereby air may pass outwardly through the container.

2. A filter device adapted to be attached to the dust bag of a vacuum cleaner, comprising a box having an integral bottom portion provided with an opening, said bottom projecting inwardly into the box, the opening in said bottom being closed by a

screen, said box having a removable comprising a ringlike member adapted to telescope with the sides of the box and a piece of screen connected to the ringlike member, said box being adapted to receive a wet sponge through which air must pass when leaving the bag and to which the dust contained in the air will adhere.

3. A filtering device adapted to be attached to a dust bag comprising, in combination, a cylindrical box having a bottom member that projects into the box, said bottom member having an opening closed by reticulated material, a cover member adapted to be attached to the open end of the box, said cover member consisting of a ring to one edge of which a screen member is attached, said box being adapted to receive a filter medium consisting of a sponge that has been moistened, and two ring members of L-shaped cross section secured to the outside of the box and adapted to clamp between them the material to which the device is attached.

4. A dust bag for vacuum cleaners formed of substantially air-tight fabric having an opening for the escape of air, a metal container located in the opening and secured to the material of the bag by means forming an air tight seal, said container having an inwardly convex bottom member provided with openings, and an outwardly convex cover member also provided with openings.

In testimony whereof I affix my signature.

CLARA M. JAQUITH.
